By Rector, Hibben, Davis & Macauley
His Atty's

UNITED STATES PATENT OFFICE.

MATHER W. SHERWOOD, OF FRANKLIN, PENNSYLVANIA, ASSIGNOR TO CHICAGO PNEUMATIC TOOL COMPANY, OF CHICAGO, ILLINOIS, A CORPORATION OF NEW JERSEY.

PNEUMATIC TOOL.

1,251,121.

Specification of Letters Patent. Patented Dec. 25, 1917.

Original application filed February 24, 1914, Serial No. 820,548. Divided and this application filed March 11, 1915. Serial No. 13,586.

To all whom it may concern:

Be it known that I, MATHER W. SHERWOOD, a citizen of the United States, residing at Franklin, in the county of Venango and State of Pennsylvania, have invented certain new and useful Improvements in Pneumatic Tools, of which the following is a specification.

My invention relates to tools operated by a motive fluid, usually compressed air and therefore commonly called pneumatic tools. The object of my invention is to produce a simple and efficient construction of tool provided with means for causing the compressed air to pass, at the will of the operator, from the cylinder, through the striking piece or anvil and also through a hollow drill bit to the cutting end thereof for the purpose of blowing out the cuttings or chips in the hole.

In the drawings, Figure 1 is a central longitudinal section of a hand drill embodying my invention but showing the handle mostly in elevation; Fig. 2 a detail view of one side of the tool structure at 90° to the sides shown in Fig. 1; Fig. 3 a section on the line 3 of Fig. 1.

For the purpose of a clear and definite description of my invention I have shown the same embodied in a type of drill known as a hand drill intended more particularly as a rock drill, but it will be understood that my invention is not to be limited thereto and that I contemplate using the same wherever applicable.

Referring to the particular embodiment of my invention as herein shown, the drill comprises a main cylinder 1, having a piston chamber 2, a piston 3 reciprocable therein and having a hammering portion or stem 3^a, a striking piece or anvil 4, a drill bit 5 having a central longitudinal passage 5^a, a front head 6, a drill chuck or socket 7 (which in the present instance is rotatable), and a suitable handle 8 secured to the cylinder by the side rods 9 which also serve to clamp and hold the front head. In Fig. 2 I have shown one side of the tool structure with one side rod only, but it will be understood that the other side is similarly equipped with a side rod.

The piston chamber 2 has communication with the live motive fluid, such as compressed air, entering the inlet connection

10 and passing through suitable ports and 55 passages governed by a distributing valve which is here in the form of a ball 11. The piston chamber is also in communication with the atmosphere through suitable ports and passages hereinafter more particularly 60 described.

When the parts are in the relative position shown in Fig. 1 with the ball valve in its left hand position, the live motive fluid enters the connection 10 and passes through 65 the ports 12 in the valve cage 13, through port 14 in the right hand valve seat 15 and through passages 16 and 17 to the front end of the piston chamber with the result that the piston is reciprocated to its rearward 70 position, that is to the left in Fig. 1.

The piston chamber is provided on its inner walls with two annular grooves 18 and 19 communicating with the exhaust ports 20 and 21 respectively. When the piston in its rearward travel has cleared the groove 18, the front end of the piston chamber will be placed at exhaust to the atmosphere and will be rapidly exhausted with the result that the live motive fluid in the 80 corners of the valve cage on the left hand side of the ball will roll the ball to the right and force it upon its seat 15 to close the port 14, it being understood that the inlet ports 12 are of restricted carrying capacity as compared with the ports and 85 passages 14, 16, and 17, that the live air on the left of the ball valve will operate such valve as described.

The valve being now seated upon the seat 90 15, the inlet port 22 in the other seat 23 will now be opened and the live motive fluid will flow therethrough and through the port 24 to the rear end of the piston chamber. As a result the piston will be reciprocated 95 forwardly and its stem 3^a will strike against the piece or anvil 4 which will impart its blow to the drill bit 5. At this time the piston is in the position shown in Fig. 1 and the rearward end of the chamber is now 100 at exhaust through the groove 19 and exhaust port 21, the ball valve being shown as just having been thrown to the left to admit the motive fluid to the front end of the piston chamber.

The exhaust ports 20 and 21 do not communicate directly to the atmosphere but through a hand operated valve in the form

of a shell 25 open at one end and closed at the other and arranged to oscillate in a chamber formed in a casing 26 extending longitudinally of the cylinder 1. This valve 5 is adapted to be manually operated by means of a handle 27 secured to the closed or solid end of the valve and arranged to move through a slot 28 in the outer wall of the casing 26. This slot is provided along one 10 edge with notches 28^a into which the handle is spring pressed and thereby held in different adjusted positions. As shown, a spring 29 is interposed between a pin or stud 30 rotatably connected with the solid 15 end of the valve and a plug 31 at the outer end of the casing 26. According to this construction, the valve 25 may be oscillated by means of the handle 27 so as to bring the exhaust ports 20 and 21 out of register with 20 the ports 32 and 33 respectively of such valve, thereby shutting off the exhaust. When the handle 27 is released, the spring 29 will move the valve 25 slightly longitudinally into engagement with one of the 25 notches 28^a. In restoring the valve 25 to open or exhaust position, the reverse operation takes place, that is, the valve 25 is moved slightly rearwardly to bring its handle out of the notch 28^a and is then swung 30 to open position. When this position is reached then the operator's hold on the valve 27 is released, and the spring 29 will force such handle into the other notches 28^a, thereby retaining such valve in its open or 35 exhaust position.

The exhaust shut-off valve 25 is provided for the purpose of enabling the motive fluid to be discharged through the drill bit at the will of the operator and to thereby 40 blow out the cuttings in the bottom of the hole made by the bit. As shown, this bit is provided with a central passage 5^a which communicates with the central passage 4^a in the anvil 4. The piston stem or extension 45 3^a is provided with one or more longitudinal grooves or flattenings 3^a, in order to permit the motive fluid at the front end of the piston 3. Every time the motive fluid is admitted to 50 the front end of the piston chamber, a portion thereof thus passes through the anvil and through the hollow steel for the purpose stated.

In the event that the supply of air delivered to the cutting end of the drill bit is insufficient so that the hole is not being properly cleared of chips or cuttings, the shut-off valve 25 is closed. The piston 3 will travel rearwardly but upon reaching 65 its rearward position, there being no com-

plete release of the motive fluid to throw the ball valve, the motive fluid will continue to flow through the anvil and through the drill bit to eject the chips or cuttings. By these means, the piston 3 is rendered inoperative and a direct and continuous supply of air is delivered from the inlet 10 through the tool and to the cutting end of the drill bit. 70

It will be understood that the rotation 75 mechanism for rotating the drill chuck forms no part of my present invention, the same constituting the subject matter of the original application Serial No. 820,548, filed February 24, 1914, now Patent 1,243,770, 80 October 23, 1917, of which this is a division; and it will also be understood that my invention is not limited to a tool structure having any rotation mechanism. 85

I claim:

1. The combination of a cylinder having ports and passages for the admission and exhaust of the motive fluid, a piston reciprocable therein, a distributing valve controlling the admission of the motive fluid to the cylinder, said cylinder having intermediate its length and governed by the piston and exhaust groove and port, a valve arranged alongside the cylinder and on the exterior thereof and having a port adapted to communicate with said last-mentioned exhaust port adapted to be oscillated to close the same, and a drill bit having a longitudinal passage for the motive fluid from the front end of the cylinder to its cutting 100 end. 90

2. The combination of a cylinder having ports and passages for the admission and exhaust of the motive fluid, a piston reciprocable therein, a distributing valve controlling the admission of the motive fluid to the cylinder, said cylinder having intermediate its length and governed by the piston an exhaust groove and port, an auxiliary cylinder arranged parallel with said first-mentioned cylinder and open at its forward 105 end and adapted to communicate with said last-mentioned exhaust port, a shell valve arranged to oscillate in the auxiliary cylinder and having a port normally communicating with the latter exhaust port and adapted to close the same, and a drill bit having a longitudinal passage for the motive fluid from the front end of the cylinder to its cutting 110 end. 115

3. The combination of a cylinder having ports and passages for the admission and exhaust of the motive fluid, a piston reciprocable therein, a distributing valve controlling the admission of the motive fluid to the cylinder, said cylinder having intermediate its length and governed by the piston, two parallel circumferential grooves and exhaust ports therefrom through the cylinder walls, a shell valve arranged along- 120 125

side the cylinder and adapted to oscillate to govern said last-mentioned exhaust ports, said shell valve having two ports adapted to register with said exhaust ports, and a drill bit having a longitudinal passage for the motive fluid from the front end of the cylinder to its cutting end.

4. The combination of a cylinder having ports and passages for the admission and 10 exhaust of the motive fluid, a piston reciprocable therein, a distributing valve controlling the admission of the motive fluid

to the cylinder, said cylinder having intermediate its length and governed by the piston an exhaust port, a valve arranged alongside the cylinder exteriorly thereof and adapted to be oscillated to close the exhaust port, and a drill bit having a longitudinal passage for the motive fluid from the front end of the cylinder to its cutting end. 15
